Fig. 2

Fig. 3

FIG. 1 is a top plan view of a play gym incorporating a catwalk and observation platform showing my new design.

FIG. 2 is a front elevation of my design as shown in FIG. 1.

FIG. 3 is a side elevation taken from the right side of FIG. 2.

The characteristic feature of my design resides in the catwalk and observation platform incorporated in a play gym, all as shown.

I claim:

The ornamented design for a play gym incorporating a catwalk and observation platform, as shown and described.
